DESIGN FOR A COAT

Albert Rauch, New York, N. Y.

Application June 26, 1941, Serial No. 101,671

Term of patent 3½ years

To all whom it may concern:

Be it known that I, Albert Rauch, a citizen of the United States, residing in New York city, in the county of New York and State of New York, have invented a new, original, and ornamental Design for a Coat, of which the following is a specification, reference being had to the accompanying drawing, forming part thereof.

Fig. 1 is a front view of a coat showing my new design, and

Fig. 2 is the rear view thereof.

I claim:

The ornamental design for a coat, substantially as shown.

ALBERT RAUCH.
